CLAIM

The ornamental design for a record holder, as shown and described.

DESCRIPTION

FIG. 1 is a front elevational view of a record holder showing my new design;

FIG. 2 is a right side elevational view, the opposite side a mirror image thereof;

FIG. 3 is a bottom plan view; and

FIG. 4 is a cross section taken along line IV—IV of FIG. 1.

FIG.2.

FIG.1.

FIG.3.

FIG.4.
